UNITED STATES PATENT OFFICE.

OLA A. ANDERSON, OF GRAND RAPIDS, MICHIGAN.

BENCH-BLOCK.

1,236,134.

Specification of Letters Patent. Patented Aug. 7, 1917.

Application filed June 26, 1916. Serial No. 106,074.

To all whom it may concern:

Be it known that I, OLA A. ANDERSON, a citizen of the United States, residing at Grand Rapids, in the county of Kent and State of Michigan, have invented certain new and useful Improvements in Bench-Blocks, of which the following is a specification.

My invention relates to improvements in 10 bench blocks for use on cabinet benches, carpenters' benches, &c., and its object is to provide a cheaply constructed bench block of metal with which the danger of dulling or injuring a plane bit, should it come in 15 contact with the surface of the block when planing lumber, is practically eliminated.

I attain this object by the construction 20 and assembling of metals shown in the accompanying drawing, in which Figure 1 is a plan of the completed block; Fig. 2 is a longitudinal section of the same on the line 2-2 of Fig. 1 showing the layers of metal 25 and the manner of assembling them to insure a perfectly safe and secure manner of 30 uniting the two metals in the construction of the block; Fig. 3 is a transverse section of the same on the line 1-1 of Fig. 1; and Fig. 4 is a plan of the base, or supporting 35 part of the block to which the softer metal is attached.

Similar numerals refer to similar parts throughout the several views shown in the drawing.

In the construction of this block I make a 35 base or supporting element 2, of cast iron, cast steel, or other suitable metal of sufficient strength to safely support the softer metal 1. While the coating of soft metal 1 may be applied to any form of metal bench 40 block, for convenience I have applied it to the bench block patented to me April 6, 1916, by Letters Patent No. 1, 184,937, the only change in the block shown in said patent being in the forming of the upper surface 45 thereof. In the former patent this was shown as a plain cast iron block. In this case the edges of the block are made flaring and the center of the upper surface is removed to form the dovetailed rim or border 50 5. I, also, drill, or form flaring holes, 3, for the purpose of strengthening the center of the softer metal.

When the core 2 has been properly prepared it is placed in a properly formed mold, as 7, as indicated in Fig. 4, and the mold, 55 around the core, is filled with some soft metal, preferably lead, solder or very soft Babbitt metal, previously melted and properly poured into the mold.

It will be readily understood that with 60 the softer metal properly prepared and poured into the mold, over and around the core or base 2, and conforming closely to the dovetailed edges, and the flaring holes 65 3 of the core, as at 5 and 6, the softer metal becomes practically coherent with the harder metal, especially if the harder metal has been properly prepared and a flux used that will cause the softer metal, in its melted state, to adhere to the surface of the harder 70 metal, as by soldering. The last mentioned condition is very desirable in the construction of these blocks, though it is not absolutely necessary.

It is not material where the holes 3, 3, 75 in the base or core 2, are located, as they are used only to strengthen the soft metal cap 1, though I prefer to have them near the front edge of the block, as indicated in Figs. 2 and 4, as by this means they act more directly to strengthen the soft metal at the edge upon which the greatest strain is exercised. However, I frequently place these holes in practically the position shown in Fig. 3, especially if making the blocks so 80 narrow, in cross section, as to preclude the possibility of locating them forward of the standard 4, as in Figs. 2 and 4, as hereinbefore suggested.

What I claim as new, and desire to secure 90 by Letters Patent of the United States, is:—

In a bench block, a broad metal base forming a thin web having downwardly and outwardly flaring holes therethrough, a dovetailed border integral with and extending 95 upward from the base, a supporting stem integral with and extending downward from the base, and a soft metal covering around, within and upward from the base and the dovetailed border and through the openings 100 in the base.

Signed at Grand Rapids, Michigan, June 23, 1916.

OLA A. ANDERSON.
